EARL B. CLARKE, OF LAFAYETTE, INDIANA, ASSIGNOR TO WESTINGHOUSE ELECTRIC & MANUFACTURING COMPANY, A CORPORATION OF PENNSYLVANIA

MEANS FOR COOLING ELECTRICAL APPARATUS

Application filed February 17, 1928. Serial No. 254,961.

My invention relates to means for cooling electrical apparatus and has particular reference to electrical transforming apparatus.

In electrical transforming apparatus and 5 the like, it is necessary to dissipate the heat generated by the operation of such apparatus in a simple and efficient manner.

One of the means now used, to which my invention has particular reference, comprises 10 immersing the electrical apparatus in an insulating and heat conducting fluid such as oil having a high dielectric strength. It has been found in such means that the surface of the tank for containing the oil did not have 15 a sufficient radiating surface for dissipating the heat generated by the electrical apparatus to raise the temperature of the oil. Therefore, to increase the radiating surface to cool the oil more quickly, a plurality of tubular 20 members were disposed in banks about the periphery of the transformer casing. These tubular banks or radiators greatly increased the radiating surface in contact with the oil and cooled the latter more quickly and effec- 25 tively.

I have found that the efficiency and usefulness of this type of apparatus may be greatly increased by blowing streams of air onto the sides of each bank so that they meet and form 30 a resultant stream of air that rises vertically upward, parallel with and in contact relationship with the heat dissipating surfaces of the radiator tubes.

My invention, however, may be more readily understood if the accompanying drawings are consulted in connection with the following description.

In the drawings:

Figure 1 is a view in elevational perspective of a transformer casing having cooling apparatus associated therewith and constructed in accordance with my invention.

Fig. 2 is a plan view of a portion of the transformer casing shown in Fig. 1 having a portion thereof broken away.

Fig. 3 is a view, similar to Fig. 2, of a modification of my invention; and

Fig. 4 is a view in side elevation of the device shown in Fig. 3.

50 Referring to Fig. 1, a system constructed

in accordance with my invention comprises a tank or casing 2 that is provided with radiators 3 that communicate with the upper and lower part of the tank 2 through pipes 4. Transforming apparatus (not shown) is disposed within the casing 2 and is connected by conducting leads to terminals 5 that are insulated from the cover 6 of the transformer casing 2 by insulating bushings 7.

The casing 2, the radiators 3 and the connections 4 contain a suitable cooling and insulating medium 2a, such as an oil of high dielectric strength, the heat generated in the transformer causing a thermal circulation of the cooling medium through the radiators 65 where this heat is transferred to the surrounding atmosphere and dissipated.

The radiators 3 comprise a plurality of vertical substantially parallel tubular members 8 that materially increase the radiating 70 surface for dissipating the heat of the oil that passes through them. To the end that air jets may be directed against the radiator tubes, I dispose about the casing 2, preferably in a region midway of its ends, an air 75 jacket or duct 9 to which radial air ducts 10 are connected. The duct 9, preferably, is separated from the casing 2 by a space 11 for permitting the normal upward movement of the heated air near the surface of the cas- 80 ing 2.

The radial air ducts 10 are disposed in facing relation on opposite sides of each of the radiators 3 and each is provided with an elongated opening or passage 12, the relation 85 being such that the air jets emitted from the openings 12 on opposite sides of a radiator 3 move into the central area of the radiator at an angle with respect to the radiator tubes 90 so that the two jets of air meet and form a single upward current of air. This upward current of air has a velocity equal to the resultant of the velocities of the two air jets that meet to form it.

Usually, the inner tubes of any radiator 3 are at higher temperature than are the outer tubes of that radiator because said inner tubes are surrounded by other heat dissipating tubes. In accordance with my invention, the 100

air jets from the openings 12 meet near these inner tubes at a relatively high velocity and, therefore, cool them efficiently. The flow of air upwardly around the surfaces of the radiating tubes from the openings 12 creates a suction effect with resultant movement of the air around these portions of the radiating tubes below said openings 12.

All of the air passageways are mounted, 10 preferably, so that they will be some distance away from the surfaces of the tank and radiators, for example, about $1\frac{1}{2}$ inches more or less. This completely prevents the air passageways from blanketing the radiator 15 and tubes.

Air may be supplied to the central air duct 9 in any suitable manner as, for example, by a centrifugal blower 15 that is driven by a motor (not shown) enclosed in a housing 16. 20 Air is directed to the chamber 9 through a conduit 17 suitably secured thereto. The blower 15 and the housing 16 are mounted, preferably, on U beams 18 that, in turn, are mounted on the transformer supporting 25 frame 19.

In Figs. 3, and 4, I have illustrated another cooling system in which radiators 3' are arranged in banks, all of them being disposed on one side of the transformer casing 2 and 30 preferably suspended from a pipe 13 receiving hot oil from the top of the transformer casing 2 and passing it into the radiators 3' from which it flows by the lower pipe 14 back into the tank 2'.

35 To thus dispose the radiators 3' in the manner illustrated in Figs. 3 and 4 is desirable because such a disposition of them leaves a large portion of the tank 2 substantially free from blanketing and, therefore, leaves the latter free to dissipate heat in an efficient manner. In this modification the number of radiators may be increased indefinitely, permitting of the size of the main tank to be decreased to a minimum.

40 A central air duct 20 is provided between the two rows 21 and 22 of radiators 3' and said duct 20 has passage forming structures 23 projecting from it into the space between adjacent radiators 3'. The radiators 3' are 45 suitably spaced apart for the reception of the structures 23 which are spaced a short distance from the surface of the radiator tubes so as not to prevent the natural circulation of air around them as set forth above. The 50 main air duct 20 is located, preferably, midway between the ends of the radiators 3'. A baffle wall 24 is mounted in each of the structures 23 so that the air will divide, a portion going toward each of the radiators. As explained above in connection with Figs. 1 and 2, an elongated port opening 12' is provided in the sides and near the top of the structures 23. The action of the air in meeting and 55 forming a current of air parallel with the tubes of the radiator is similar to that ex-

plained above in connection with Figs. 1 and 2.

A centrifugal blower 15' supplies air at the desired pressure to the main air duct 20. The air blower 15' may be driven in any 70 suitable manner as, for example, by a motor 25 whose shaft may be directly coupled to the shaft of blower 15'.

An oil circulating device comprising a motor 26 and a pump 27 driven thereby may 75 be utilized with the form of my invention illustrated in Figs. 3 and 4, the pump 27, preferably, being inserted in the lower pipe 14 between the transformer tank 2 and the radiators 3'.

The above-described apparatus is especially suited for cooling very large self-cooled transformers and makes possible the application of heavy overloads on a normally self-cooled transformer or provides means 85 for reducing the number of radiators that would normally be necessary if air and oil under forced circulation were not utilized.

It will be apparent to those skilled in the art that my invention is readily applicable 90 to any type of heat-radiating apparatus and is no wise limited to the cooling of electrical transformers. It will also be apparent to those skilled in the art that a particularly desirable feature of my invention lies in the 95 method of cooling a plurality of tubes having radiating surfaces which comprises generating and directing a plurality of currents of air to the said tubes so that the said currents meet and form a resultant current of 100 air that passes upwardly in contact with the surfaces of the tubes.

Various changes may be made in my invention without departing from the spirit and scope thereof as set forth in the appended 105 claims.

I claim as my invention:

1. In combination, a tank, a plurality of radiators mounted on said tank, said radiators being disposed in spaced banks around the periphery of said tank, a central air duct embracing said tank having radial air ducts, each of said radial air ducts having a port opening on one side of a bank of said radiators, and means for supplying air under 110 pressure to said central air duct.

2. In combination, a radiator comprising a plurality of vertically disposed tubular members, means for blowing air upwardly adjacent to said tubular members including 115 pairs of air ducts disposed on opposite sides of said radiators, each pair of said ducts having elongated openings facing each other, and sloping baffle plates disposed above said openings for causing the air issuing from said openings to meet at an angle near the center of the radiator and assume a vertical resultant direction of movement.

3. A cooling apparatus including a tank 120 containing a heated liquid, radiators asso- 130

ciated therewith and disposed around the periphery of said tank, a central air duct spaced from and embracing said tank and having discharge ducts extending therefrom, 5 each discharge duct being provided with an air outlet port adjacent to a radiator, and means for supplying air under pressure to said central air duct.

4. A cooling apparatus for a transformer 10 including a tank containing a heated liquid, radiators associated therewith for removing heat from said liquid, a central air duct around said tank, and means for directing a cooling fluid from said duct to the surfaces 15 of said radiators, said means including a plurality of tapered box-shaped ducts each radiating from the central duct along the surface of said radiators.

In testimony whereof I have hereunto subscribed my name this 9th day of February, 20 1928.

EARL B. CLARKE.
